CLAIM

We claim the ornamental design for a door, as shown and described.

DESCRIPTION

FIG. 1 is a perspective view of a door.

FIG. 2 is a front view of the door of FIG. 1, of which a back view is identical.

FIG. 3 is an enlarged fragmentary section view of the door of FIG. 1, taken along line 3-3 of FIG. 2.

FIG. 4 is a top view of the door of FIG. 1, of which a bottom view is identical; and,

FIG. 5 is a right side view of the door of FIG. 1, of which a left side view is identical.

In FIG. 3, the lateral broken lines depict the limits of the enlarged view taken from FIG. 2. The middle wavy broken lines and the broken-line hatching indicating a sectional view are not intended to illustrate the internal construction of the door. The aforementioned broken lines in FIG. 3 form no part of the claimed design.
